[57] **CLAIM**

The ornamental design for a drive spoon for a reversible impulse sprinkler, as shown and described.

DESCRIPTION

FIG. 1 is a top and side perspective view of a drive spoon for a reversible impulse sprinkler showing my new design;

FIG. 2 is a top plan view thereof;

FIG. 3 is a right side elevational view thereof, taken in the direction of line 3—3 of FIG. 2;

FIG. 4 is a front end elevational view thereof;

FIG. 5 is a rear end elevational view thereof;

FIG. 6 is a bottom plan view thereof;

FIG. 7 is a top, rear perspective view thereof; and,

FIG. 8 is a bottom, front perspective view thereof.
